UNITED STATES PATENT OFFICE.

CHARLES E. STIPP, OF DILLON, MONTANA.

FLY-TRAP.

1,167,855.

Specification of Letters Patent. Patented Jan. 11, 1916.

Application filed July 15, 1912. Serial No. 709,531.

To all whom it may concern:

Be it known that I, CHARLES E. STIPP, a citizen of the United States, residing at Dillon, in the county of Beaverhead, State 5 of Montana, have invented certain new and useful Improvements in Fly-Traps; and I do hereby declare the following to be a full, clear, and exact description of the invention, such as will enable others skilled in the 10 art to which it appertains to make and use the same.

This invention relates to improvements in attachments for screen doors or windows and has for one of its objects to provide, in 15 combination with the frame of a screen door, electrically charged screens for electrocuting flies.

Another object of the invention is to provide a screen door having the ordinary 20 screens attached thereto, and screens of larger mesh secured to the door on the inside and outside so as to form spaces between the ordinary screen and the ones of larger mesh.

25 A further object is to provide a screen door having screens of large and small mesh, each of which is adapted to be connected to one terminal of an electric circuit, the screens of large mesh being disposed on opposite sides of the screen of small mesh and closely adjacent thereto, but out of contact therewith, so that the insects passing through the outer screen will come in contact with the inner and outer screens and 30 complete a circuit through their bodies whereupon they will be electrocuted.

With these and other objects in view, the invention consists in the construction, combination and arrangement of parts as will 40 be more fully hereinafter described and pointed out in the claims, but it will be understood that changes in the specific structure may be made within the scope of the claims, without departing from the spirit of 45 the invention.

In the drawings: Figure 1 is a front elevation of the door casing and screen door showing my invention applied. Fig. 2 is a vertical section on the line 2—2 of Fig. 50 1, looking toward the right in Fig. 1. Fig. 3 is an enlarged detailed view in section of one of the contact members between the top of the door and the upper part of the door casing, the section being on the line 3—3 55 of Fig. 1. Fig. 4 is a view similar to Fig.

3, the section being taken on the line 4—4 of Fig. 1.

Referring now particularly to the drawings, in which is shown a preferred form of screen door and attachment made in accordance with my invention, A represents the door casing, on the lower face of the upper cross strip 1 of which is secured a pair of contact plates 2 and 2' by means of the screws 3 and 3', which form binding posts 65 or terminals. On a shelf 4 located above the door frame is a spark coil 5, the primary winding of which is connected by means of the wires 7 in an electric circuit, as a lighting circuit, or one of greater voltage, while 70 the secondary winding is connected by the wires 6' to the aforementioned screws 3 and 3'. The screen door B comprises the side strips 7, the upper and lower strips 8, and the middle strip 9, between which in the 75 upper and lower panels is secured the usual fine meshed screen 10.

Secured on the inner and outer faces of the aforementioned strips, and covering the upper and lower panels are the supplemental screens 11, which are of larger mesh than the screen 10, to provide openings large enough for flies or other insects to gain ready access to the space between the screens 10 and 11, from both sides of the door. Secured to the upper face of the top strip 8 of the door B by means of the screws 8' and 8'' are the spring contact fingers 12 and 12', adapted when the door is closed to engage 85 with the plates 2 and 2' on the upper strip 90 of the door frame.

The wire 13 is secured at one end to the inner or fine meshed screen 10 while the wire 13' is bared at two points as seen in Fig. 5, said bared portions being wound 95 around a strand of each of the larger meshed screens 11. Between the bared portions a section of insulation 13'' is disposed to insulate the wire 13' from the screen 10. It will readily be seen that when the screen door is closed and any flies or other insects pass far enough through the meshes of either of the screens 11 to come in contact with said screen 10, the secondary circuit 100 will be completed through the bodies of the insects, killing them. The opposite ends of the wires 13 and 13' are secured to the screws 8' and 8'', respectively. Thus when the door is closed and an insect bridges the 105 screens 10 and 11, the current is conveyed 110

through the plates 2 and 2' by means of wires 6, and through the contact fingers 12 and 12' to the screens 10 and 11 by means of the wires 13 and 13' which connect said screens with the spring fingers 12 and 12'.

5 While I have shown a device applied to screen doors, it will readily be understood that the same may be applied to window screens.

10 What is claimed is:

1. The combination with a screen door frame, of an insect trap consisting of screens of large and small mesh, said screens of larger mesh being secured to said door on opposite sides of the screens of small mesh and out of contact therewith, means to connect to the screens of small mesh one side of a source of current and to connect the screens of large mesh to the other side whereby when an insect in passing through a screen of large mesh contacts simultaneously with said screen of large mesh and the screen of small mesh, a circuit is completed through its body.

15 2. In combination with a screen door frame, of an insect trap comprising screens of small mesh on the door, means to connect a source of current at one terminal to said screens comprising contact plates secured

20 to the upper portion of the door and frame, screens secured to the door on opposite sides

thereof and being of large mesh to form inlet openings for insects, and similar means to connect the opposite terminal of said source of current to said screens of large mesh.

25 3. A device for electrocuting insects comprising sets of reticulated metal sheets arranged in parallel relations, the openings of the outer set of sheets being larger than the openings of the other sheets, to permit the electrical connections between the sets of sheets being insulated from each other, and electrical connections between the sets of sheets and opposite sides of a source of electric energy.

4. In a device for electrocuting insects, the combination with a screen door frame, of screens of different mesh mounted on the frame in parallel and insulated relation to each other, the screens of large mesh being outside the others, and means for sending an electric current of high frequency through the screens, and the body of an insect which has bridged the screens of different mesh.

50 In testimony whereof, I affix my signature, in presence of two witnesses.

CHARLES E. STIPP.
